United States Patent [19]

Sasaki et al.

[11] Patent Number: Des. 307,274

[45] Date of Patent: ** Apr. 17, 1990

[54] **AUDIO TELECONFERENCE EQUIPMENT WITH ACOUSTIC ECHO CANCELLER**

[75] Inventors: **Kiyoshi Sasaki; Keigo Kawasaki**, both of Tokyo, Japan

[73] Assignee: **NEC Corporation**, Tokyo, Japan

[**] Term: **14 Years**

[21] Appl. No.: **263,491**

[22] Filed: **Oct. 27, 1988**

[30] **Foreign Application Priority Data**

Apr. 27, 1988 [JP] Japan 63-17398

[52] U.S. Cl. **D14/243; D14/240;**
D14/140; 379/440; 379/420

[57] **CLAIM**

An audio teleconference equipment with acoustic echo canceller, as shown.

DESCRIPTION

FIG. 1 is a front, top and right side perspective view of an audio teleconference equipment with acoustic echo canceller, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG.1

FIG.2

FIG.3

FIG.4

FIG. 5

FIG. 6

FIG. 7
